DISPLAY RACK FOR ARTICLES OF CLOTHING

Arthur J. Lovald, 7606 36th Ave., Kenosha, Wis.

Filed May 7, 1962, Ser. No. 70,015

Term of patent 7 years

(Cl. D80—10)

FIG. 1

FIG. 1 is a perspective view of a display rack for articles of clothing showing my new design.

FIG. 2 is a side elevational view thereof.

FIG. 3 is a top plan view thereof.

I claim:

The ornamental design for a display rack for articles of clothing, substantially as shown.
